G. C. WHITNEY

TRAIN INDICATION SYSTEM

Original Filed March 27, 1924

INVENTOR

Gilbert C. Whitney

Patented Aug. 17, 1926.

UNITED STATES PATENT OFFICE.

GILBERT C. WHITNEY, OF NEW YORK, N. Y.

TRAIN INDICATION SYSTEM.

Original application filed March 27, 1924, Serial No. 702,262. Divided and this application filed February 11, 1925. Serial No. 8,401.

This invention relates to train describers and train indicators in general wherein means are provided to indicate the position or describe the movement of a train or car 5 on a railway track and in particular to novel means for accomplishing the aforementioned results with minimum apparatus especially when installed on tracks not equipped with a signal system.

10 This present application is a division of my co-pending application filed March 27, 1924, Serial No. 702,262, for train indication system.

In my above mentioned application I have 15 set forth, at length, the general objects and operation of my invention as carried into effect or superposed on existing signalled railway track territory and it is assumed that reference to said application will be 20 had.

In this divisional application I have shown my invention arranged in a system of train indication, without the customary track rail insulated joints in general use in 25 railway signaling and indication systems and therefore my system readily permits the use of both rails of the track for the propulsion system on electrically operated railways:—thus the general objects appear 30 and additional objects will be disclosed as the specification proceeds and I will point out the novel features in the appended claims.

I have provided two figures to clearly 35 portray the preferred application and simplify the operation description but I wish it to be understood that I do not restrict or limit myself to such application of my invention—it is so shown merely to disclose 40 the broad idea underlying my invention. It will be observed that the reference characters are not consecutive and this is because I have preferred that this invention be disclosed and described with the same reference characters for similar parts as my previously referred to application and thus 45 make this disclosure concise as well clearly understood.

Fig. 1 is a diagrammatic illustration of 50 my invention.

Fig. 2 is a diagram representing the value 55 and variation of current flow in the indication circuits due to train travel along the track section. Fig. 2 may also be assumed 60 to show variation of the illumination emit-

ted by the indicator lamps as the train proceeds along the track section.

Referring to the drawing—In Fig. 1, I have shown the two rails 6, 7, of a railway track as continuous but it will be appreciated that they may be made in various lengths and connected together by splice plates and bonded or otherwise to form a continuous rail circuit as is customary but, track rails 6, 7, remain electrically insulated (in so far 65 as the indication circuit, hereinafter explained, is concerned) from each other by the wood ties or other appropriate means in general use.

As the means to impress alternating current supply on the track rails for the working of my invention I have shown three 70 transformers 9 to supply energy to the track at selected points, approximately though not necessarily equidistant. Said transformers 75 9 receive energy from source of energy supply alternator 18 by way of power wires 17, 16, and branch wires 15, 14. The secondary windings of transformers 9 are connected to the track rails 7, 6, by means of track wires 80 11, 10. Connected in series with each of the secondary windings of transformers 9, I show primary windings 35 of transmitter 85 transformers 34 and inductively coupled to said primary windings 35, I show transmitter secondary windings 36, each of which is included in a transmission circuit 37, 38. Included at the receiver end of said transmission circuits I show receiver transformers 39 to the secondary windings of which 90 are shown connected indicator lamps 42. I show track rails 6, 7, short-circuited by reactances C D E at suitable places, approximately at mid-points, between the points 95 where energy supply track wires 10, 11 are connected to said track rails. The characteristics of all apparatus is proportioned such that the induced current supplied to the respective indicator lamps 42 is a maximum when the track rails 6, 7, are short-circuited, as by a train wheel shunt, at the corresponding points of energy supply track wires 10, 11, and said maximum induced current flow to the respective lamp 100 42 varies as said train wheel shunt moves either way from said points with slow reduction until said train wheel shunt passes a track short-circuiting reactance and thereafter at a rapidly increasing rate, as predetermined by the value of reactance 105 em-

110

ployed, and as illustrated in Fig. 2, wherein a train is assumed to be a point only for the purpose of clarity.

From the foregoing description it will be evident that the movement of the train is synchronously indicated by the change in illumination caused by the change in value of induced current supplied to said lamp as the train moves along the track section and 10 without the use of insulated joints in the track rails.

Hereinbefore, I have referred to the fact of track rails 6 and 7 being electrically insulated from each other by the wood ties or 15 other appropriate means and it will be evident that, even though the wood ties are an insulator when dry, they may be wet due to rain and their value as an insulator be thereby impaired. It is customary, therefore, to apply only low voltages to the track rails 6 and 7 and especially so with this 20 type of system without insulated track rail joints and with indication transmitters 34 at comparatively close intervals, as dictated 25 by the spacing between trains. It is the general custom to arrange the indicator lamps at a central point for a given territory which may be of considerable extent and, owing to the great number of circuits 30 involved, economy demands that small wires be used in the transmission circuit and naturally only a small transmission current can be tolerated, otherwise the loss in transmission would not only be prohibitive but 35 would interfere with the indication as hereinafter pointed out. Starting then, with the necessarily low track circuit voltage I provide inductive coupling 34 to act as a step-up transformer to provide a higher transmission circuit voltage and the corresponding 40 transmission current for indication purposes is of the order of 0.015 ampere and less. Now, as is well-known, an indication lamp of high voltage and low wattage (one 45 (1) watt and less) is not commercially possible because of the inability to provide a lamp filament which will heat on a current flow of the above mentioned order of 0.015 ampere and less and accordingly I provide 50 receiver transformer 39 of the step-down type and wherein the resultant induced indicating current flow to lamp 42 is of the order of 0.080 to 0.350 ampere and at an operating voltage of from approximately 55 one (1) volt to five (5) volts. Thus it will be evident that, in the use of transformer 39, means have been provided to effect an indication on a very small transmitted power and with a minimum in the losses incident 60 to transmission. A minimum in the losses of transmission is important for the reason that the variation in current flow in the rail circuit, as between the train or car at several points within the influence territory of an indication lamp, is small and every last

effort must be made to conserve the results, of the variation, during transmission to the indication device.

Referring to Fig. 2, the solid irregular line traces out the value of current supply to indicator lamp 42CD as the train wheel shunt approaches and traverses track sections CD, said current reaching a maximum when the train wheel shunt is adjacent track wires 10, 11, for that section and reaching a practical minimum rapidly, as aforesaid, when and as said train wheel shunt passes a short distance beyond said section: similarly, the dot and dash line illustrates similar conditions for the track section and corresponding indicator lamp DE: and so on to the end of the system, as will be appreciated. Obviously, a train is not a point and the representative lines in the diagram will broaden and overlap as the train point takes on the dimension, length.

It will be understood that the variation in the induced current flow to the lamp as the train wheel shunt moves on the track rails is due to the fact of the rail resistance being increased or decreased in the circuit which includes winding 35 for the respective section.

While, it may be assumed that the characteristic variation of illumination is the same for train position in each half of a track section, it will be appreciated that the direction of movement of the train is emphasized by the indication of the lamps for the adjacent track sections.

It should be noted that track reactances C D and E may be eliminated in which event the operation of my system will be less contrastly distinctive.

Attention is directed to the fact that, while I have shown, in Fig. 2, that the irregular lines represent the variation in current supply to the lamp, they also represent the variation of the illumination of the respective indicator lamps as a car proceeds over the track section. I desire it to be distinctly understood that, although the irregular lines of Fig. 2, show a variation in illumination between the extremes, as the car passes over the track section (that is, between no illumination and full illumination) the indicator lamps may be partially illuminated at all times, for example, with 20% illumination, when the track section is not occupied by a car, and with illumination variation between 20% illumination as a base (at the time the car enters the track section) to 100% illumination when the car wheel shunt is on the track at the point where track wires 10 and 11 for the respective section are attached—all as determined by the design of apparatus in each installation. The fact that the lamps may be arranged to be partially illuminated at all times provides a means for continuously in-

dicating that the system is in working order.

I wish it to be understood that, while I have only illustrated two completely equipped track sections and portions of two adjacent sections, in practice a complete territory would be equipped and the indicator lamps assembled in an indicator board or track model diagram at the desired location.

The transmission circuit 37, 38, is generally composed of No. 19 A. W. G. or smaller wires owing to the fact that on account of low wattage lamps being used the small line current permits of using small conductors, thus contributing to low installation costs.

Obviously, the arrangements and illustrations which I have shown and described are merely illustrative and do not exhaust the various embodiments and forms which I have made, or that anyone ordinarily skilled in this art could make without departing from the novelty, spirit and scope of the broad idea of means underlying my invention.

Having thus described my invention I claim and desire to secure by Letters Patent:—

1. A train indication system; characterized by a plurality of sources of energy impressed upon the track rails of a railway track, each source of energy having an inductive coupling included in series therewith, and an indicator lamp inductively coupled to each inductive coupling, each indicator lamp indicating the presence and movement of a car on said railway track, both rails of said track electrically continuous and without insulated joints.

2. A train indication system; characterized by a section of railway track both rails of which are maintained electrically continuous and without insulated joints, a source of energy impressed upon the track rails at a plurality of points, an inductive coupling included in an energy supply wire to each of said points, and an indicator lamp inductively coupled to each inductive coupling, for synchronously indicating the presence and movement of a car on said railway track.

3. A train indication system comprised of a section of railway track, a source of energy, transformers for supplying said energy to said track at a plurality of points, reactance elements bridging the rails of said track between the points of energy supply, and means for utilizing said energy to indicate the presence and movement of a train on said section of railway track, both rails of said track electrically continuous and without insulated joints.

4. A train indication system comprised of a section of railway track, a source of energy, transformers for supplying said energy to said track section at a plurality of points, an indication transmitter connected

in series with each of said transformers, and an indicator lamp connected with each of said indication transmitters, for indicating the movement of a train on said section by variation in light emitted by said lamp, both rails of said track electrically continuous and without insulated joints.

5. A train indication system comprised of a section of railway track, a source of energy, transformers for supplying said energy to said track section at a plurality of points, an indication transmitter in series with the energy supply to the track rails of said track, and an indication receiver for each transmitter, each transmitter responsive controlling the corresponding receiver as a train moves on said section of railway track, each receiver indicating the movement of a train on said section of railway track, both rails of said track electrically continuous and without insulated joints.

6. A train indication system, comprised of a section of railway track, a source of energy, transformers for supplying said energy to said track section at a plurality of points, indication transmitters inductively coupled to said supply, a transmission circuit for each transmitter, and remotely located indication means synchronously responsive to variations in the energy flow in said transmission circuit caused by the movement of a train on said section of railway track, both rails of said track electrically continuous and without insulated joints.

7. A train indication system comprised of a section of railway track, a source of energy, transformers for supplying said energy to said track at a plurality of points, indication transmitters inductively coupled to said track, and indication receivers including indicator lamps inductively coupled with said transmitters, said lamps energized from said source and with partial illumination when said track is unoccupied, said illumination varying as a car moves on said track, both rails of said track electrically continuous and without insulated joints.

8. A train indication system comprised of a section of railway track, a source of energy, a plurality of transformers for supplying said energy to said track at a plurality of points, transformers in series in the energy supply to said track, transformers connected to said second mentioned transformers, and indicator lamps connected to said third mentioned transformers, both rails of said track section electrically continuous and without insulated joints.

9. A train indication system comprised of a section of railway track, a source of energy, transformers for supplying said energy to said track at a plurality of points, indication transmitters inductively coupled to said track, and indication receivers connected to said transmitters, each receiver at

times indicating the presence of a train on said track and at times continuously indicating the movement of a train on said track, both rails of said track electrically continuous and without insulated joints.

10. A train indication system comprised of a section of railway track, a source of energy, transformers for supplying said energy to said track at a plurality of points, 10 transformers in series with the secondary of the first mentioned transformers, transmission circuits in series with the secondary of the second mentioned transformers, a third

transformer in series with each of said transmission circuits, and indicator lamps connected to the secondary of said third transformers, both rails of said track electrically continuous and without insulated joints.

11. The invention set forth in claim 2, distinguished by the indicator lamps being 20 assembled to form a train indicator diagram and arranged in consecutive order.

Signed at Brooklyn in the county of Kings and State of New York.

GILBERT C. WHITNEY.
